UNITED STATES PATENT OFFICE.

JOSEPH J. CAVANAUGH, OF LOS ANGELES, CALIFORNIA.

AUTOMOBILE-RADIATOR ATTACHMENT.

1,313,791.

Specification of Letters Patent. Patented Aug. 19, 1919.

Application filed October 23, 1918. Serial No. 259,312.

To all whom it may concern:

Be it known that I, JOSEPH J. CAVANAUGH, a citizen of the United States, residing at Los Angeles, in the county of Los Angeles, State of California, have invented certain new and useful Improvements in Automobile-Radiator Attachments; and I do hereby declare the following to be a full, clear, and exact description of the invention, such as will enable others skilled in the art to which it appertains to make and use the same.

This invention relates to new and useful improvements in water cooling systems for automobile engines, and particularly to an attachment for the radiator.

One object of the present invention is to provide a novel and improved device which is arranged to be applied to the radiator in place of the ordinary cap, for the purpose of preventing escape of water when traveling over rough and uneven ground.

Another object is to provide a device of this character which will prevent the water from getting too hot and which will readily permit the escape of any steam arising from the water in the radiator.

Other objects and advantages will be apparent from the following description when taken in connection with the accompanying drawing.

In the drawing:

Figure 1 is an elevation of the device applied to an automobile radiator.

Fig. 2 is a vertical sectional view taken on the line 2—2 of Fig. 1, slightly enlarged.

Fig. 3 is a horizontal sectional view taken on the line 3—3 of Fig. 2.

Fig. 4 is a vertical sectional view taken on the line 4—4 of Fig. 2.

Referring particularly to the accompanying drawing, 10 represents a portion of an automobile radiator and 11 the filling tube thereof, said tube being externally threaded, as shown.

A casing 12 is provided with an internally threaded lower end 13 for engagement on the said filling tube 11 of the radiator. At a point, approximately midway of the height of the casing, there is formed a horizontal partition wall 14 having a central opening 15 formed with upwardly tapering walls, as shown. Formed vertically through the partition, at one side of the opening, is an opening 16, and disposed through this

opening is the lower end of a bent pipe or goose-neck 17, the other end being directed downwardly toward the center of the opening 16. Adjusting nuts 18 and 19 are threadedly engaged on the lower portion of the goose-neck, above and below the wall 14, as shown in the drawing. These nuts are so adjusted that the pipe 17 will stay firmly in place when adjusted in opening 16, whereby steam can escape upwardly through said pipe. At a point in the wall 14, diametrically opposite to the opening 16, there is formed another opening 18', and disposed upwardly through this opening is the vertical leg 19', of an L-shaped member 20. The horizontal portion of this member 20 extends transversely beneath the central opening 15, and carried by said portion is a vertical stem 21 which extends upwardly through the center of the opening 15. Slidably disposed on this stem 21 is an upwardly tapering valve body 22, the upper end of which is formed with an upwardly extending projection 23 which is arranged to nearly engage in the downwardly turned end of the pipe 17, as said valve rises by the upward pressure of water in the filling tube. An aluminum band 24 is secured around the outer face of the valve 22 for engagement with the tapered wall 15 of the opening 15. A retaining nut 25 is engaged on the upper end of the leg 19' to hold the L-shaped member in proper adjusted position. Hinged to the upper open end of the casing is a cover 26, the intermediate portion being open as shown at 27. A latch 28, coöperating with the casing, is carried by the other side of the cover to hold the same in closed position.

When traveling over rough or uneven ground the water in the radiator splashes upwardly and is wasted. Also, by reason of the fact that the steam in the water is confined within the radiator, the water becomes heated more quickly and retains the heat for a longer period, thus greatly impairing the working of the engine, and preventing the proper cooling of the water in the jacket. By reason of the fact that the cover is open, and the valve normally open, the heat can escape upwardly through the opening 15, and through the pipe 17, thus causing a more rapid radiation and cooling of the water. This will greatly aid in keeping the engine cylinders at the proper tem-

perature, and add to the efficiency of the engine. As the water in the radiator splashes upwardly it strikes the lower side of the valve and lifts the same into engagement with the seat in the opening 15, thus preventing any escape of water, while at the same time the projection on the valve nearly engages the goose-neck pipe and permits any steam to pass quickly through the goose-neck pipe as will be readily understood.

What is claimed is:

1. An attachment for an automobile radiator including a casing arranged for engagement with the filling tube of a radiator, a floating valve within the casing arranged to be seated by splashing water in the radiator, and a steam escape means adjacent the valve.
  2. An attachment for an automobile radiator including a casing arranged to be engaged with the filling tube of the radiator, a vertical guide mounted in the casing, a valve seat in the casing, a floating valve mounted to slide on the guide and engage said seat, and a steam escape pipe located adjacent the valve seat to permit escape of steam when the valve is engaged with the seat.
3. An attachment for a radiator filling tube of an automobile including a casing, a horizontal wall in the casing having a central opening forming a valve seat, a member mounted in the casing and having a stem extending upwardly through said opening, a valve slideable on the stem and arranged to engage said seat to prevent escape of water from the radiator, said wall having an opening adjacent the central opening, a bent steam escape pipe disposed for vertical adjustment through the last-named opening, the valve having a vertical projection arranged to enter but not close the upper end of the bent pipe, whereby steam will escape from the radiator through said pipe when the valve is engaged on its seat.

In testimony whereof, I affix my signature, in the presence of two witnesses.

JOSEPH J. CAVANAUGH.
